US0D1059290S

(12) **United States Design Patent** (10) **Patent No.:** **US D1,059,290 S**
(45) **Date of Patent:** **** Jan. 28, 2025**

(54) **CAPACITOR**

(71) Applicant: **AmRad Manufacturing, LLC**,
Universal City, TX (US)

(72) Inventor: **Robert M. Stockman**, Palm Coast, FL
(US)

(73) Assignee: **AmRad Manufacturing, LLC**,
Universal City, TX (US)

(**) Term: **15 Years**

(21) Appl. No.: **29/764,072**

(22) Filed: **Dec. 28, 2020**

(57) **CLAIM**

The ornamental design for a capacitor, substantially as shown and described.

DESCRIPTION

FIG. 1 is a perspective view of a capacitor;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is another perspective view thereof in an alternate state.

The dotted broken lines depict the bounds of the claimed design, while all evenly spaced broken lines depict environment and form no part of the claimed design.

1 Claim, 5 Drawing Sheets
